US00D823786S

(12) **United States Design Patent** (10) **Patent No.:** **US D823,786 S**
(45) **Date of Patent:** **** Jul. 24, 2018**

(54) **ASYMMETRICAL SOLAR PANEL BRACKET ASSEMBLY**

(71) Applicant: **Pegasus Solar Inc.**, San Jose, CA (US)

(72) Inventors: **Erich Kai Stephan**, Newport Beach, CA (US); **Glenn Harris**, Sausalito, CA (US)

(73) Assignee: **PEGASUS SOLAR INC.**, Richmond, CA (US)

(**) Term: **14 Years**

(21) Appl. No.: **29/522,558**

(22) Filed: **Mar. 31, 2015**

(51) LOC (11) Cl. **13-02**

(52) U.S. Cl.

USPC **D13/102**

(57) **CLAIM**

The ornamental design for an asymmetrical solar panel bracket assembly, as shown and described.

DESCRIPTION

FIG. 1 is a perspective view of an asymmetrical solar panel bracket assembly showing our new design;

FIG. 2 is a top plan view thereof;

FIG. 3 is a bottom plan view thereof;

FIG. 4 is a first side view thereof;

FIG. 5 is a second side view thereof;

FIG. 6 is a third side view thereof; and,

FIG. 7 is a fourth side view thereof.

The broken lines shown in the figures illustrate the portions of the design that form no part of the claimed design.

1 Claim, 5 Drawing Sheets
